UNITED STATES PATENT OFFICE.

JAMES MUNTON, OF MAYWOOD, ILLINOIS.

TIRE-ROLLING MACHINE.

SPECIFICATION forming part of Letters Patent No. 401,713, dated April 16, 1889.

Application filed September 17, 1888. Serial No. 285,565. (No model.)

To all whom it may concern:

Be it known that I, JAMES MUNTON, a citizen of the United States, residing in Maywood, in the county of Cook and State of Illinois, have invented a new and useful Improvement 5 in Tire-Rolling Machines, of which the following is a specification.

My invention relates to improvements in the manufacture of tires from blooms, as set forth 10 and described in Letters Patent of the United States, Nos. 363,842 and 363,843, granted to me May 31, 1887, and No. 381,505, granted to me April 17, 1888. As described in said patents, after the annular bloom is cast, its top 15 portion is sheared or cut off by revolving rolls having cutter flanges or collars, and then the sheared bloom is edged in, densified, and rolled to the required diameter by a rolling-machine having vertical and horizontal rolls 20 to operate upon all four faces of the bloom or tire either simultaneously or consecutively.

My present invention consists in combining with the shearing or cutting rolls a stop or device to limit the approach of the cutting- 25 rolls toward each other, so that the cutter-flanges of the rolls may come sufficiently close together to sever the annulus from the bloom, and at the same time prevent the cutters from injuring each other by being forced together 30 so that they strike or touch.

It also consists in combining with the vertical cutter-rolls a pair of horizontal edging-rolls, which may be brought into play the moment the shearing or cutting operation is 35 completed and the severed annulus removed, so that in this way, without removing the bloom from the mill or machine containing the cutter-rolls, the rolling operation and densification of the bloom may be continued 40 as long as the bloom retains sufficient heat. When the cutting operation is completed, the cutting-flanges of the cutter-rolls span or almost span the horizontal thickness of the bloom, so that no more rolling can then be 45 done by the cutter-rolls without causing the opposing cutter-flanges to meet or strike against each other; but by combining in the same mill with the vertical cutter-rolls a pair of horizontal edging-rolls the rolling and densification of the bloom may be indefinitely 50 continued at the same heat that the cutting

is done, as the first effect of the horizontal or edging rolls which bear against the top and bottom faces of the bloom is to diminish the vertical thickness of the bloom and to increase 55 its horizontal thickness; and as soon as the horizontal thickness has thus been increased sufficiently to prevent the opposing flanges of the cutter-rolls from meeting the cutter-rolls may be again brought into play and operated 60 simultaneously, or, if desired, alternately, with the edging-rolls.

It also consists in combining with the cutter-rolls and edging-rolls two exterior pressure-rolls, which tend in their operation to 65 densify the bloom and roll the bloom backward or to a smaller diameter, or to hold it at a fixed diameter under the action of the edging and cutter rolls. These two exterior pressure-rolls operate in conjunction with 70 the exterior cutter-rolls. By this combination of the edging-rolls and the exterior rolls with the cutter-rolls the rolling and densification of the bloom may be continued to any desired extent at the same heat with the cutting operation, and a bloom or tire may thus 75 be produced of much superior density, quality, and texture to the ordinary hammered bloom, as the fraying and injurious effects of hammering are entirely avoided.

My invention also consists in mounting the inside vertical pressure-roll or its shaft on a separate slide from that which carries either or both of the edging-rolls, so that the downward or vertical pressure which operates the movable edging-roll will not increase the friction 85 of the horizontal slide which carries the inside vertical pressure or cutter roll in cases where the edging and rolling operations are being carried on simultaneously.

My invention also consists in mounting the two horizontal edging-rolls and the hydraulic cylinder for operating the movable or pressure edging-roll in the same horizontally-sliding frame upon which the two exterior pressure-rolls are carried, so that downward or vertical pressure upon or between the edging-rolls will not increase the friction of the horizontally-sliding frame when the edging-rolls and the exterior pressure-rolls are brought to 95 bear simultaneously upon the tire, as is sometimes desirable.

My invention also consists in the novel devices and novel combinations of parts and devices herein shown and described, and more particularly pointed out in the claims.

5 In the accompanying drawings, which form a part of this specification, and in which similar letters of reference indicate like parts, Figure 1 is a side elevation of a machine or mill embodying my invention. Fig. 2 is a plan view. Fig. 3 is an end view. Fig. 4 is a vertical longitudinal section. Fig. 5 is a cross-section on line 5 5 of Fig. 2. Figs. 6 and 7 are cross-sections on lines 6 6 and 7 7 of Fig. 2. Fig. 8 is a detail plan view. Figs. 9 15 and 10 are cross-sections of the tire, showing its form after the shearing operation is completed and after being operated upon by the edging-rolls, respectively, and illustrating the action of the edging-rolls to increase the horizontal thickness of the tire, so that the flanges of the cutting-rolls will not meet. Fig. 11 is a vertical section showing ordinary box-rolls, which may be substituted for the cutter-rolls when the mill is being used for rolling or finishing tires or rings.

In the drawings, A represents the frame or bed of the machine; B and B', the cutter-rolls; C C, the two exterior pressure-rolls, and D D' the horizontal or edging rolls.

30 The cutter-rolls B B' are preferably both furnished with cutter-flanges or bevel-collars b b, the combined width of the flanges b b being equal to the horizontal thickness of the bloom when the cutting operation is completed. The shaft B² of the exterior cutter-roll, B, is journaled in stationary bearings B³ on the main driving-frame A, and it is driven from the main driving-shaft E through the bevel-gears E' and E². Its lower end is supported in a vertically and longitudinally adjustable cup-shaped box or bearing, B⁴, the adjustment of which is effected by the wedge B⁵ and the screws B⁶ and B⁷. The shaft B⁸ of the movable cutter-roll B' is journaled in bearings B⁹ B¹⁰ on the horizontal slide or carriage F, which reciprocates on suitable guides, F', on the main frame of the machine. The slide F is connected by rods or bars F² with the piston F³ of the hydraulic cylinder F⁴, by which said slide F is reciprocated to force the cutter-roll B' against the bloom in opposition to the roll B.

55 The movement of the movable or pressure roll B' is limited by an adjustable stop, f, so that the cutter-flanges b b of the rolls B B' may approach sufficiently near to sever the top portion or annulus of the bloom and still not quite meet and thus injure each other. This stop f preferably consists of a screw threaded in the bar f', which is secured to the frame A by the rods f² f³. The screw is furnished with a hand-wheel, f³, for turning it, and with a jam-nut, f⁴.

60 The rolls C C and the edging-rolls D D' are preferably all carried by or mounted upon the same slide or carriage, G. The slide G is re-

ciprocated in suitable guides, G', on the main frame of the machine by a hydraulic cylinder, G², the piston G³ of which is connected to said slide. The vertical rolls C C and the horizontal roll D are all three journaled directly on the slide G; but the vertically-movable horizontal roll D' is journaled in suitable bearings, D², on a vertically-reciprocating supplemental slide, H, carried on the slide G.

The supplemental slide H is reciprocated (see Figs. 4 and 6) in its guides H' on the sliding frame G by a hydraulic cylinder, H², and piston H³, the stem H⁴ of the piston 80 being connected to the slide H. An adjustable stop, h, limits the vertical movement of the edging-roll D', so that the tire or bloom may be edged down to any desired width. This stop h preferably consists of a hand-wheel nut on a screw-threaded stem, h', secured to the piston H³. As the two opposing horizontal or edging rolls D and D' and the hydraulic cylinder H², for forcing them together, are mounted upon or carried by the 90 same main slide or carriage, G, the pressure of the rolls D and D' will oppose and neutralize each other and not be exerted against the guides G' of the slide G, nor in any way increase the friction or the force required to reciprocate said slide G on the main frame A.

The vertically non-movable edging-roll D is journaled in bearings D³ on the reciprocating slide or carriage G, and it is driven from the main driving-shaft E through the spur-gears E³ E⁴ and shaft E⁵, which shaft is connected to the shaft D⁴ of said roll D by a hollow shaft or sleeve, D⁵, having a spline, d, to permit the reciprocating movement of the slide G and shaft D⁴.

105 The bearings C' C' of the two vertical rolls C C are mounted adjustably on the slide G, Figs. 1 and 2, so that they may be adjusted closer together or farther apart, as may be required in rolling tires of different diameters. 110 This adjustment is preferably effected by furnishing the slide G with slots c, in which the bearings or boxes C' fit, the position of the boxes in the slots being adjusted by a series of thin blocks, plates, or wedges, c', as indicated 115 in Fig. 2.

K K, Fig. 2, are a pair of exterior guide-rolls mounted on adjustable slides K' K', which reciprocate on transverse guides k on the main frame A. The positions of the guide-rolls are adjusted by screws k' k', having sprocket-wheels k² k², chains k³ k³, and sprocket-wheels k⁴ k⁴ on the shaft k⁵, which is furnished with a hand-wheel, k⁶, for turning it.

120 L L represent the pipes by which the water or fluid under pressure is admitted to the hydraulic cylinders F⁴, G², and H² from the pumps and accumulator customarily employed in tire-rolling mills for operating the pressure or movable rolls. Valves L' control 130 the admission or escape of the fluid-pressure as required.

The cutter-rolls B B' are removably secured upon their shafts, so that they may be removed and replaced by others when worn or when required in rolling blooms or tires or 5 rings of different sizes and cross-sections. The cutter-rolls B B' may also be removed and replaced by ordinary box or other rolls—such, for example, as shown in Fig. 11—when it is desired to use the same mill for plain rolling 10 as contradistinguished from cutting and rolling.

The shaft of the movable or pressure roll B' and the shaft of the movable or pressure edging-roll D' are not driven except by friction 15 with the tire or bloom being rolled. In practice I have also not found it necessary to drive the vertical rolls C C except by friction with the tire.

In operation the bloom the top of which is 20 to be cut off is first placed in the mill and the cutter-roll B' forced up against it by the fluid-pressure admitted into cylinder F⁴. As the cutting operation proceeds under the action of the cutter flanges or collars b b, the rolls B 25 B' also roll the bloom, increasing its diameter and diminishing its horizontal thickness. After the cutting operation is completed the annulus severed from the bloom is removed with a crane, and then the slide G is advanced 30 until the edging-rolls D D' are brought astride of the bloom, when the pressure is admitted into the hydraulic cylinder H² and edging-roll D' forced down upon the tire, the pressure being relieved at this time upon the 35 inside cutter-roll, B'. After the edging operation is continued for a while the horizontal thickness of the tire will be thereby so increased, as indicated in Figs. 9 and 10, that the cutter-roll B' may be again brought into 40 play without causing the cutter-flanges to meet and injure each other. At the same time with the edging operation the exterior pressure-rolls, C C, may also be brought into 45 play to further densify the metal.

By mounting the hydraulic cylinders F⁴ and G² at opposite ends of the machine the slides which carry the various movable or pressure rolls may be more conveniently operated. The connecting-rods F², which connect 50 the slide F⁴ with its operating-piston F³, pass astride of the stationary exterior roll, B, and its shaft.

When the mill or machine is being used for plain rolling or finishing the bloom into a 55 tire, plain rolls being substituted for the cutter-rolls B B' on the shafts B² B³, the stop f is set so as to gage the horizontal thickness of the tire by limiting the movement of the inside pressure-roll toward the exterior stationary roll. This stop f thus serves a very 60 useful and important function, especially where the inside pressure-roll is operated by a hydraulic cylinder and piston, as contradistinguished from a screw. By means of this 65 stop I am enabled to prevent any wavy irregularities in the horizontal thickness of the tire, which might otherwise be occasioned by

the hydraulic or somewhat elastic pressure which forces the inside pressure-roll against the tire. By means of this stop f, in combination with the stop h, which limits the movement of the vertical pressure-roll, the vertical thickness and the longitudinal thickness both of the tire may be accurately gaged and limited, so that the finished tire 75 may be made very uniform.

I claim—

1. The combination, with a pair of cutter-rolls, of a pair of edging-rolls, substantially as specified.

2. The combination, with a pair of horizontal or edging rolls, D D', said roll D' being journaled in a vertically-movable slide, of a hydraulic cylinder and piston for operating said vertically-movable slide, an exterior vertical roll, and an inside movable pressure-roll mounted on a separate slide from said edging-rolls, substantially as specified.

3. The combination, with stationary exterior cutter-roll, B, of inside movable pressure cutter-roll, B', a slide upon which it is mounted, and a fixed stop on the frame of the machine limiting the movement of said slide, substantially as specified.

4. The combination, with cutter-rolls B B', of slide F, hydraulic cylinder F⁴, piston F³, connected to said slide, and adjustable stop f on the frame of the machine, limiting the movement of said slide to prevent the cutter-flanges of said rolls from meeting, substantially as specified.

5. The combination, with an exterior stationary roll and its shaft, of inner movable roll and its shaft, a slide upon which said pressure-roll is mounted, a hydraulic cylinder and piston, and a connection between said slide and piston passing astride of said stationary roll or its shaft, substantially as specified.

6. The combination, with exterior vertical fixed roll, B, of inside pressure-roll, a movable slide on which said pressure-roll is mounted, two edging-rolls and two exterior vertical pressure-rolls, C C, and a main slide, as G, upon which said edging-rolls and said exterior pressure-rolls are all mounted, substantially as specified.

7. The combination, with edging-rolls D D', of a movable main slide, G, carrying both said rolls, substantially as specified.

8. The combination, with edging-rolls D D', of a movable main slide, G, carrying both said rolls, and a supplemental vertical slide mounted upon said main slide and in which one of said edging-rolls is journaled, substantially as specified.

9. The combination, with edging-rolls D D' and a movable main slide, G, carrying both said rolls, and a supplemental vertical slide mounted upon said main slide and in which one of said edging-rolls is journaled, of a hydraulic cylinder and piston mounted on said main slide for operating said supplemental slide, substantially as specified.

10. The combination, with edging-rolls D D', of a movable main slide, G, carrying both said rolls, and exterior vertical rolls, C C, mounted on said main slide G, substantially as specified.
11. The combination, with main slide G, of supplemental vertical slide H, mounted on said main slide, edging-roll D, journaled on said main slide, edging-roll D', journaled on 10 said supplemental slide, a hydraulic cylinder and piston carried by said main slide for operating said supplemental slide, exterior vertical rolls, C C, mounted on said main slide, and a fixed exterior roll opposing said rolls C C, substantially as specified.
12. The combination, with main slide G, of supplemental vertical slide H, mounted on said main slide, edging-roll D, journaled on 20 said main slide, edging-roll D', journaled on said supplemental slide, a hydraulic cylinder, H², and piston H³, carried by said main slide, for operating said supplemental slide, exterior vertical rolls, C C, mounted on said main slide, a fixed exterior roll opposing said rolls C C, and a hydraulic cylinder, G², and piston G³, mounted on the frame of the machine, for operating said main slide G, substantially as specified.
13. The combination, with main slide G, of 30 supplemental vertical slide H, mounted on said main slide, edging-roll D, journaled on said main slide, edging-roll D', journaled on said supplemental slide, a hydraulic cylinder, H², and piston H³, carried by said main slide, for operating said supplemental slide, exterior vertical rolls, C C, mounted on said main slide, a fixed exterior roll opposing said rolls C C, a hydraulic cylinder, G², and piston G³, mounted on the frame of the machine, for operating said main slide G, an inside vertical pressure-roll, a separate horizontal slide upon 40 which it is mounted, and a hydraulic cylinder, F², and piston F³ at the opposite end of the machine from said hydraulic cylinder and piston G² G³, substantially as specified.
14. The combination, with main slide G, of edging-rolls D D', carried thereby, shaft D⁴, shaft E⁵, and sliding sleeve D⁵, connecting said shafts D⁴ and E⁵, substantially as specified.
15. The combination, with a stationary vertically-driven roll-shaft, B², of a horizontal slide carrying an inside pressure-roll shaft, a horizontal slide carrying exterior pressure-rolls, and hydraulic cylinders and pistons mounted on opposite sides of said stationary roll-shaft for operating said slides, substantially as specified.
16. The combination, with a stationary vertically-driven roll-shaft, B², of a horizontal slide carrying an inside pressure-roll shaft, a horizontal slide carrying exterior pressure-rolls, and hydraulic cylinders and pistons mounted on opposite sides of said stationary roll-shaft for operating said slides, and a pair 60 of edging-rolls mounted upon said slide G, substantially as specified.
17. The combination, with edging-rolls D D', of a movable main slide carrying both said edging-rolls, a stationary exterior roll, a movable or pressure inside roll opposing said stationary exterior roll, and an independent slide, upon which said inside pressure-roll is mounted, substantially as specified.
18. The combination, with a stationary exterior roll, of an inside pressure or movable 70 roll, a horizontal slide, F, upon which it is mounted, a main slide, G, a supplemental slide, H, mounted on said main slide, edging-roll D, mounted on said main slide G, and edging-roll D', mounted in said supplemental 80 slide H, substantially as specified.
19. The combination, with a stationary exterior roll, of an inside pressure or movable roll, a horizontal slide, F, upon which it is mounted, a main slide, G, a supplemental 85 slide, H, mounted on said main slide, edging-roll D, mounted on said main slide G, edging-roll D', mounted in said supplemental slide H, and hydraulic cylinders and pistons at opposite ends of the machine, for operating said 90 horizontal slides F and G, substantially as specified.
20. The combination, with a stationary exterior roll, of an inside pressure or movable roll, a horizontal slide, F, upon which it is 95 mounted, a main slide, G, a supplemental slide, H, mounted on said main slide, edging-roll D, mounted on said main slide G, edging-roll D', mounted in said supplemental slide H, and a hydraulic cylinder and piston 100 mounted in said slide G, for operating said supplemental slide H, substantially as specified.
21. The combination, with a stationary exterior roll, of an inside pressure or movable 105 roll, a horizontal slide, F, upon which it is mounted, a main slide, G, a supplemental slide, H, mounted on said main slide, edging-roll D, mounted on said main slide G, edging-roll D', mounted on said supplemental slide 110 H, a hydraulic cylinder, H², and piston H³ on said main slide G, for operating said supplemental slide H, and hydraulic cylinders F⁴ G² and pistons F³ G³ at opposite ends of the machine, for operating said horizontal slides 115 F and G, substantially as specified.
22. In a tire-rolling mill, the combination of horizontal edging-roll D, vertically-movable or pressure edging-roll D', and a stop to limit the downward movement of said edging-roll D', substantially as specified.
23. In a tire-rolling mill, the combination, with a horizontal edging-roll, D, of vertically-movable edging-roll D', a vertically-movable slide upon which it is journaled, a hydraulic 125 cylinder and piston for operating said slide, and a stop for limiting its movement, substantially as specified.
24. The combination, in a tire-rolling mill, of an exterior vertical stationary roll, an inside movable pressure-roll, a hydraulic cylinder and piston for operating it, and a stop 130

for limiting its movement, substantially as specified.

25. The combination, in a tire-rolling mill, of an exterior vertical stationary roll, an inside movable pressure-roll, a hydraulic cylinder and piston for operating it, and a stop for limiting its movement, a horizontal edging-roll, D, a movable edging-roll, D', a hy-

draulic cylinder and piston for operating it, and a stop for limiting its movement, substantially as specified.

JAMES MUNTON.
